UNITED STATES PATENT OFFICE.

LAWRENCE A. SUBERS, OF LAKEWOOD, OHIO.

MACHINE FOR CONSTRUCTING A LAMINATED COHESIVE INTERWOUND FABRIC BAND.

Application filed December 18, 1920. Serial No. 430,444.

To all whom it may concern:

Be it known that I, LAWRENCE A. SUBERS, a citizen of the United States, and a resident of Lakewood, county of Cuyahoga, and 5 State of Ohio, have invented a new and useful Improvement in Machines for Constructing a Laminated Cohesive Interwound Fabric Band, of which the following is a specification, the principle of the invention being 10 herein explained and the best mode in which I have contemplated applying that principle, so as to distinguish it from other inventions.

The present invention relates to an improved apparatus for constructing various sizes of laminated cohesive interwound fabric bands from series of groups of close lying parallel threads or yarns. The present machine is similar in general operation 15 to those shown in my issued United States Letters Patents Nos. 1,189,751, dated July 4, 1916, 1,201,774, dated October 17, 1916, and 1,223,636, dated April 24, 1917, but in the machines of these patents no provision 20 was made for adjusting the distance on the tubular mandrel from the point at which the series of groups of close lying parallel yarns or threads were interwound thereabout to the rubber box in which the yarns were coated 25 30 with liquid rubber or other desired adhesive material.

Long series of experiments with the types of machines mentioned and improved modifications thereof showed that a tubular mandrel of rectangular cross section seemed to 35 offer less resistance to the passage of the yarns thereover, and that it was necessary to have more than half a turn around the mandrel of the yarns in a dry state, before 40 treating with liquid rubber or other adhesive in an enclosed rubber container, in order that practically no displacement of the yarns in relation to their angle of winding should take place.

45 It was also found that the crossing points of the series of groups of yarns upon the mandrel were not thoroughly coated with adhesive unless these crossing points were changed while in the rubber container, and 50 the passage of these yarns or threads over a certain angular incline on the mandrel to a predetermined greater width and a similar angular decline to the previous normal width accomplishes this displacement and 55 replacement without affecting their predetermined position in the band.

A small angle of winding, as from two to five degrees to the longitudinal axis of the mandrel, has been found the most advantageous, since it gives the least amount of 60 stretch in the finished band when under strain, and practically the maximum amount of production, and as it is seems to be the least angle at which practically no displacement of the yarns or threads occur. Owing 65 to the retention of practically the same angle of winding, the distance necessary for a half wrap around the mandrel varies with different width of mandrels being practically twice the distance for a 1" width mandrel as 70 a $\frac{1}{2}$ " width mandrel. Consequently, it is advisable in making different width of bands to be able to vary the distance from the position of winding of the yarns or threads to the rubber box and in the machine herein- 75 after described this is accomplished by mounting the reel standards on a sliding auxiliary base and moving this auxiliary base and reels to or from the rubber box according to the width of mandrel being 80 used. To the accomplishment of the foregoing and related ends, said invention, then, consists of the means hereinafter fully described and particularly pointed out in the 85 claims.

The annexed drawing and the following description set forth in detail certain mechanism embodying the invention, such disclosed means constituting, however, but one of various mechanical forms in which the 90 principle of the invention may be used.

In said annexed drawings:—

Fig. 1 is a plan view of the machine; Fig. 2 is a side view of the machine; Fig. 3 is a sectional view on line $a-a$ Fig. 2; Fig. 4 is 95 a partial sectional view of the sliding gear mounting of the power shaft in the reel standard; Fig. 5 shows a plan view of a narrow mandrel, with the yarn cages in section and a portion of the rubber box; Fig. 100 6 shows a plan view of a wider mandrel and the increased length required from the yarn cage to the rubber box over that shown for the mandrel in Fig. 5; Fig. 7 is a continuation of Fig. 6 showing the mandrel extended 105 through the rubber box and with the yarns removed.

The present machine which is of the same general type as those shown in my previously mentioned patents, is provided with 110 a suitable frame A^{23} in which is mounted a motor A or other power source, and

a power shaft A³, the motor being operatively connected to the shaft by means of a belt A² or in any other suitable manner.

The interwinding mechanism consists of 5 a series of concentric tubes B⁵, B⁶, B⁷, and B⁸, to which, respectively, are rigidly secured the reels B, B¹, B² and B³. The tubes are supported by bearing rings mounted therebetween and each tube and bearing ring 10 is provided with four longitudinal channels serving as guides to the groups of yarns or threads Y from the spools S carried by each reel. At the inner ends of the tubes B⁵, B⁶, B⁷ and B⁸, are respectively attached yarn cages B⁹, B¹⁰, B¹¹ and B¹² which serve to 15 guide the four groups of yarns or threads onto a mandrel C, suitably mounted in the frame and alinged with the axis of said tubes.

20 Thus far the construction is similar in general features to the machines of my previously mentioned patents, in which similar yarn cages are employed to wind the threads or yarns, and these reels are rotated simultaneously by means of suitable driving mechanism to be described in detail hereinafter. It will be clear from the patents mentioned that reels B and B² are to rotate in one direction and reels B¹ and B³ in 25 the opposite direction, but at the same speed so that the four yarn groups from each reel will be wound upon the mandrel in the necessary spaced relation. Thus the groups of 30 yarns from reel B are wound in spaced relation on the mandrel and those of reel B¹ over them but in the opposite direction but 35 equally spaced, while the groups from reel B² are wound over those of reels B and B¹ but in the same direction and between the 40 spaces of the groups from reel B and the groups from reel B³ in the same direction but between the spaces of the groups from reel B¹. The whole number of groups of 45 yarns are drawn lengthwise along the mandrel as the reels rotate, the relative speeds of the two actions determining the angle of winding.

In the base A²³ of the machine is guide-way A⁵⁰ on which is slidably mounted a sub-base or plate A²⁴, the gibbs A²⁷ being employed to retain the plate in the base. Mounted on this plate or sub-base A²⁴ are standards or uprights A²¹ and A²² spaced apart, the end standard A²² having a 55 threaded bushing or nut A²⁶ which has threaded engagement with a worm screw A²⁵, which is rotatably mounted in a suitable bushing A⁵¹ of the base, the worm screw having a handle and crank A⁵² by which 60 it may be rotated to move the plate or sub-base longitudinally of the machine.

These two uprights carry the four reels and the concentric tubes being provided with upper bearing portions for the tubes. 65 The reels are suitably mounted on the tubes

which are rotatably mounted in the standards, the reel B having a bevel gear A¹³ attached thereto, a similar bevel gear A¹⁴ being attached to the reel B¹, these two bevel gears meshing with another bevel gear A¹² which 70 is mounted on a vertical shaft A¹¹ carried by the standard. The reels B² and B³ are similarly driven through bevel gears A¹⁹ and A²⁰ driven from the bevel gear A¹⁸ mounted on the shaft A¹⁷ carried by standard A²¹. To 75 drive these shafts A¹¹ and A¹⁷, a longitudinal shaft A⁸ is mounted in suitable bearings A⁵⁴ on the standards, this shaft having a driving gear A⁷ meshing with a gear A⁶ carried by the standard, which is mounted 80 on a short shaft A⁵⁵ carrying another gear A⁵ in mesh with a gear A⁴ slidably mounted on the drive shaft A³ of the machine a long key way A⁵⁶ and key A⁵⁷ being employed to allow such movement. The standard A²¹ 85 has a suitable bearing A⁵⁸ which slidably receives the shaft A⁸, the gear A⁴ being mounted in such standard so as to move therewith.

In front of the yarn cages is the mandrel 90 C which passes through a rubber box D suitably mounted and having rubber supplying mechanism D¹, the mandrel extending through the rubber box. The dry yarns in their interwound state pass along the 95 mandrel, through the rubber box D where they are treated with liquid rubber or other adhesive and thence to a series of pulling and drying rolls E mounted at the end of the machine. 100

In Figures 5 and 6 are shown narrow and wide mandrels C and the proportionate length from the yarn cages B¹² to the rubber box D required for the same angle of interwinding. The yarns or threads are 105 wound on the spools in close lying parallel groups Y and in order that these yarns retain their position when wound upon the mandrel C and treated with rubber in the rubber cup D, and not roll on themselves 110 and rope up it was found necessary that they should have slightly more than half a turn around the mandrel as illustrated.

When using a wide mandrel the reel standards and reels are moved backward by 115 moving the sliding base A²³, thus giving a greater length of mandrel upon which the groups of yarns or threads are wound, and when a narrow mandrel is used the reels are moved forward, so that in all cases at 120 least half a wrap around the mandrel is obtained before the yarns or threads are treated with rubber or other adhesive.

In Fig. 7, which is a continuation of Fig. 6, is shown the mandrel and its angularly increasing and decreasing width by which the yarn groups in passing thereover are exposed to the action of the liquid rubber in the rubber box, change their crossing points Y¹ of interwinding and again resume these 130

crossing points, thereby coating these normally covered points with rubber or other adhesive substance. This angle of inclination C^1 of the mandrel to its greater width 5 and corresponding declination C^2 to its former normal width is determined by the width of mandrel employed, and the angle of interwinding. When making a wider band, using a wider mandrel, changing also 10 the point of winding accordingly, it is necessary to use spools of threads having more yarns or threads wound in a group thereon or in terms of the trade "more ends up" in order to have the yarns or threads cover the 15 mandrel, since the number of spools remain the same on each reel.

Other modes of applying the principle of my invention may be employed instead of the one explained, change being made as regards 20 the mechanism herein disclosed, provided the means stated by any of the following claims or the equivalent of such stated means be employed.

I therefore particularly point out and distinctly claim as my invention:—

1. In a machine for constructing a laminated cohesive interwound band from groups of yarns or threads, the combination of a base, a fixed mandrel carried by said 30 base, a guideway on said base, mechanism for winding such yarn groups on said mandrel adjustably mounted on said base, and means for adjusting the position of such winding mechanism relative to the fixed 35 mandrel.

2. In a machine for constructing a laminated cohesive interwound band from groups of yarns or threads, the combination of a base, a fixed mandrel carried by said 40 base, a guideway on said base, a sub-base slidably mounted in said guideway, means for adjusting the position of said sub-base relative to said fixed mandrel, and winding mechanism mounted on said sub-base and 45 adapted to wind such yarn groups on said mandrel in all positions of such sub-base.

3. In a machine for constructing a laminated cohesive interwound band from groups of yarns or threads, the combination 50 of a base, a fixed mandrel carried by said base, a guideway on said base, a sub-base slidably mounted in said guideway, means for adjusting the position of said sub-base relative to said fixed mandrel, and winding 55 mechanism mounted on said sub-base and adapted to wind such yarn groups on said mandrel in all positions of such sub-base, and driving means for such winding mechanism operative in all positions of the latter.

60 4. In a machine for constructing a laminated cohesive interwound band from groups of yarns or threads, the combination of a base, a fixed mandrel carried by said base, a guideway on said base, a drive shaft 65 mounted on said base, a sub-base mounted

in said guideway, means for adjusting said sub-base along said guideway relative to said fixed mandrel, winding mechanism mounted on said sub-base and movable therewith and adapted to wind such yarn groups on said 70 mandrel in all positions, driving means for said winding mechanism carried by said sub-base and operatively connected to said drive shaft in all positions, whereby said yarn groups may be wound on said mandrel 75 in predetermined position relative to a fixed point thereon, the positions varying with the size of mandrel employed.

5. In a machine for constructing a laminated cohesive interwound band from 80 groups of yarns or threads, the combination of a fixed mandrel on which the groups of yarns or threads are wound, the means for winding said yarn groups about said mandrel, means for varying the position of said 85 winding means along said mandrel and means of temporarily changing the normal crossing points of said groups of yarns upon said mandrel and of changing back to normal said crossing points while still upon said 90 mandrel.

6. In a machine for constructing a laminated cohesive interwound band from groups of yarns or threads, the combination of a fixed mandrel on which the groups of 95 yarns or threads are wound, the means for winding said yarn groups about said mandrel, means for varying the position of said winding means along said mandrel in respect to a fixed point at which is formed a 100 predetermined angular increase of width of said mandrel with a corresponding angular decrease of width to change the crossing points of the said groups of yarns thereon, the portion of mandrel so affected being 105 within the rubber box and exposing the crossing points of said groups of yarns or threads to the action of liquid rubber or other adhesive therein.

7. In a machine for constructing a laminated cohesive interwound band from groups of yarns or threads, the combination of a fixed mandrel on which the groups of yarns or threads are wound, the means for winding said yarn groups about said mandrel, means for varying the position of said 110 winding means along said mandrel in respect to a fixed point at which is formed a predetermined symmetrical angular increase of width of said mandrel with a corresponding symmetrical angular decrease of width to change the crossing points of the said groups of yarns thereon, the portion of mandrel so affected being within the rubber 115 box and exposing the crossing points of said groups of yarns or threads to the action of liquid rubber or other adhesive therein.

Signed by me, this 14th day of October, 1920.

LAWRENCE A. SUBERS.
